(57) **CLAIM**

The ornamental design for a dispenser as shown and described.

DESCRIPTION

FIG. 1 is a front perspective view of a first embodiment of a dispenser of the present invention showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dashed lines in the drawings are for the purpose of illustrating portions of the device, which form no part of the claimed design. The dot dashed lines in the drawings define the bounds of the claimed design and form no part thereof.

1 Claim, 6 Drawing Sheets
